UNITED STATES PATENT OFFICE.

OSCEOLA R. COOK AND LEONARD HINDS, OF PROVIDENCE, RHODE ISLAND;
SAID COOK ASSIGNOR OF HIS RIGHT TO SYLVESTER EASTMAN, OF
SAME PLACE.

HAIR-CLIPPING MACHINE.

SPECIFICATION forming part of Letters Patent No. 431,965, dated July 8, 1890.

Application filed August 13, 1886. Serial No. 210,841. (No model.)

To all whom it may concern:

Be it known that we, OSCEOLA R. COOK and LEONARD HINDS, citizens of the United States, residing at Providence, in the county of Providence and State of Rhode Island, have invented a new and useful Improvement in Hair-Clipping Machines, of which the following is a specification.

Our improvement relates to the form of the lower or stationary cutting-plate, whereby the machine may be fulcrumed on the surface to be clipped and a rocking motion imparted to the machine for the purpose of gradually varying the length of the hair, as in the operation of "shingling" the hair, and our invention also relates to the details of construction, as hereinafter described, and set forth in the claims.

The drawings hereunto annexed represent a hair-clipping machine embodying the features of our invention.

Figure 1 is a top view with the "pressure-plate" removed. Fig. 2 is a sectional view on line X X, Fig. 1. Fig. 3 is a side view of a portion of the machine, the handle having been removed. Fig. 4 is a transverse sectional view on line W W, Fig. 3. Fig. 5 is a detached and top view of the pressure-plate, and Fig. 6 is a diagram showing the effect of a "rocking motion."

A denotes the lower or stationary cutting-plate, and A' the upper or movable cutting-plate, each having the serrated edges provided with teeth *i* and spaces *i'*, as is usual in machines of this class. The plate A is attached rigidly to the handle B. The opposing handle B' is pivoted at P, and is extended to form an arm *a*, whose end engages a notch *a'* in the rear edge of the movable plate A'. Short studs *b* *b'* project from the upper surface of the stationary cutting-plate A, entering slots *c* *c* in the movable plate A', and serving both as guides to control the reciprocating motion of the plate A and also as a stop to limit its motion in either direction. The plate A' is held against the plate A, so as to insure the proper cutting action of the edges of the teeth *i*, by means of the curved pressure-plate C, whose forward edge rests in a groove *d* in the upper surface of the movable cutting-plate A'. At the opposite or

rear side of the pressure-plate a hub *e* is formed, having a hole *e'*, which fits loosely the pivotal pin P. The nut D enables the cutting-plates to be brought together with any desired pressure. Between the handles B B' we place the bent blade-spring E, whose tension maintains the handles apart when in their normal position, with the movable cutting-plate A' against the stud *b*.

We make the machine as narrow as possible at the cross-section passing through the pivotal pin P, gradually increasing it in width to afford a sufficiently long cutting-edge and making the lower plate A "fan-shaped," and thereby permitting the free use of the machine in situations otherwise inaccessible. This result we accomplish by extending the fixed handle B forward of the pivotal pin P and expanding it laterally to afford a surface, upon which the lower plate A is securely fastened. From the pivotal pin P rearward the handles B B' are slightly curved upward for a short distance, and from the pivotal pin forward the entire under surface, formed in part by the forward extension of the fixed handle and in part by the stationary cutting-plate A, is curved, forming a circular arc, with its convexity downward and tangential to the oppositely curved section of the handles B B'. This conformation, which is a distinguishing feature of our improved clipping-machine, enables the convex surface of the lower plate to be placed against the surface to be clipped, and a rocking motion to be imparted to the machine as it is simultaneously moved forward and the cutting action of the toothed edges at the same time continued. The convex surface resting upon the surface to be clipped serves as a fulcrum, upon which the cutting-edges are raised by depressing the handles, and vice versa, and thereby varying the length of the hair while the operation of cutting is carried on. In Fig. 6 the result of this rocking motion in varying the length of the hair is illustrated by a diagram, in which the line 1 2 indicates the surface over which the machine denoted by the curved line 3 is to pass. At the end 1, the handles being raised, the cutting-edges are brought close to the line 1 2, cutting the hair short. As the machine is advanced and its

cutting action continued, the handles are gradually depressed uniformly with the forward motion of the machine to the position at the opposite end of the line 1 2, cutting the 5 hair on the line 1 4.

We do not confine ourselves to any particular shape or amount of curvature, nor is it necessary that the curvature should extend entirely to the forward or cutting edge, as the 10 portion of the lower cutting-plate occupied by the cutting-teeth *i* may remain a plane-surface, if desired, for convenience of construction, it being easier to cut and grind the edges of the teeth in a plane than in a curved surface.

15 We are aware that hair-clipping machines have been heretofore made provided with a curved bottom plate upon which the machine rested and upon which it was rocked while employed in the operation of hair-cutting.

20 Such we do not claim, broadly, as such a curved bottom plate was shown in Patent No. 330,535, granted to Whittier and Donlon, November 17, 1885. One of the distinguishing features of our present invention, however,

25 consists in the relation of the curved rocking surface to the plane of the cutting-teeth, said plane being made tangential to the curved surface upon which the machine rests and upon which it is rocked, thereby allowing the 30 under surface of the cutting-teeth to rest upon the surface to be clipped and their plane to coincide with the surface to be clipped. If the machine is gradually moved forward and at the same time uniformly rocked upon its

35 lower curved surface, the compound motion of the machine will cause the plane of the cutting-teeth to describe a straight line, as illustrated in Fig. 6 of the drawings. This action of the machine is very essential to per-

40 forming the operation of shingling, from the fact that at each of the vibratory movements of the movable covering-plate the hair is clipped nearly or quite the entire length of the cutting-teeth, and in case the plane of

45 the teeth does not describe a straight line as the result of the compound motion of the machine, as above described, the cutting-teeth at each vibration of the cutting-plate will form a ridge or "step."

We are aware that a curved plate has been secured to the under surface of the comb-plate, forming a bearing upon which the head of the machine rocks as the machine is operated. Such a curved plate was shown in Letters Patent of the United States, No. 330,535. Such we do not claim; but

What we claim as of our invention, and desire to secure by Letters Patent, is—

1. In combination, the movable cutting-plate and pivoted actuating-handle, the stationary cutting-plate and fixed handle attached thereto, said stationary plate and fixed handle being curved between the cutting-edge and the axis of the pivoted handle, and a series of cutting-teeth formed upon the corresponding edges of the stationary and movable plates, and said teeth lying in a plane which is tangential to the curved section of said stationary plate, substantially as described.

2. In combination, the stationary cutting-plate and fixed handle attached thereto, the movable cutting-plate and pivoted actuating-handle, said stationary plate and fixed handle being curved substantially in the arc of a circle between the cutting-edges and the axis of the pivoted handle, said curved section having its convex side downward and forming a rocking surface upon which the machine rests when in operation, substantially as described.

3. In combination, the stationary cutting-plate and fixed handle attached thereto, the movable cutting-plate and pivoted actuating-handle, said stationary plate and fixed handle being curved substantially in the arc of a circle between the cutting-edges and the axis of the pivoted handle with its convex side downward, and a pressure-plate curved substantially in the arc of a circle with its convex side upward, said pressure-plate being held on the pivotal pin of the actuating-handle with its edge resting on said movable plate, substantially as described.
